Application January 4, 1939, Serial No. 249,221
In Germany January 4, 1938

5 Claims. (Cl. 179—171)

This invention relates to amplifying arrangements particularly adapted for uniform amplification of broad frequency bands including very low frequencies.

5 Wide band amplifiers having uniform amplification or frequency-independent characteristics are of considerable importance in electrical arts, and especially in television. Hitherto, the construction of such amplifiers have been exceedingly difficult and costly and, in many cases, could only provide uniform amplification at the cost of non-uniform time delay of signals of different frequency known as non-linear phase response characteristic. This invention provides a relatively simple and cheap means of obtaining uniform amplification through a wide band of frequencies and at the same time preserving uniform phase response.

Accordingly, it is an object of this invention 20 to provide an improved wide band amplifier.

Another object of the invention is to provide a simple wide band amplifier having uniform amplification and time delay.

Other objects of my invention will become apparent upon reading the detailed description, together with the drawings.

In the drawings,

Fig. 1 schematically shows a single stage amplifier having embodied therein impedances chosen in accordance with my invention,

Figs. 2, 3, 5 and 6 show modifications of the embodiment in Fig. 1 in more detail and structural elements shown in Fig. 1; while

Fig. 4 shows a circuit arrangement for reducing the effect of the stray capacity of a large condenser.

As is well known, the frequency dependency of an amplifier is first of all determined by the frequency dependency of the coupling means provided between the individual amplifying stages, such as the impedance Z_a in the anode circuit of an amplifying tube, the impedance Z_2 in the grid circuit of the succeeding tube and the coupling impedance Z_1 between the anode circuit and the grid circuit. Furthermore, the frequency-dependency of an amplifier, more particularly at low frequencies, is materially affected by the impedance Z_k which is inserted in the cathode lead for obtaining a suitable grid bias and which usually comprises a resistance and a condenser connected in parallel therewith. When using tubes having a plurality of grids, the screen-grid lead may further include an impedance Z_s which serves for smoothing the screen-grid voltage and the common lead of

anode and screen grid may comprise an impedance Z_c (such as the internal impedance of the source of anode voltage). These impedances, also, affect the frequency-dependency of the amplifier.

Considering all of the above mentioned impedances, we obtain the diagram of connections of an amplifying stage represented in Fig. 1.

The present invention allows by means of such a circuit arrangement, which includes one or more frequency-dependent impedances, to obtain a frequency-independent amplification i. e. a frequency-independent ratio between the voltage e_2 set up between the output terminals A_1-A_2 and the voltage e_1 set up between the input terminals E_1, E_2 .

The amplifier may comprise a plurality of amplifying stages of the type illustrated in Fig. 1, in which case the invention allows not only of rendering each individual stage frequency-independent, but also to compensate in one stage the frequency-dependency of another stage.

According to the present invention the impedance Z_a in the anode-circuit and the impedance Z_2 between the output terminals of the amplifying stage consist for this purpose of a resistance in series with impedances which are proportional respectively to the impedance Z_k in the cathode lead, to the impedance Z_s in the screen-grid lead, to the impedance Z_c in the common anode- and screen-grid lead, which impedances form part of the said amplifying stage and/or of another amplifying stage, whereas the impedance Z_a furthermore comprises impedances proportional to the coupling impedance Z_1 in the said amplifying stage and/or in another amplifying stage.

The arrangement of an amplifying stage according to the invention is represented in Fig. 2. As appears therefrom, the anode impedance Z_a consists of a resistance R_a in series with impedances $\alpha Z_s, \beta Z_c, \gamma Z_k$ and δZ_1 which are proportional to the impedances Z_s, Z_c, Z_k and Z_1 respectively, whereas the impedance Z_2 between the output terminals A_1 and A_2 consists of a resistance

$$\frac{1}{\delta} R_a$$

in series with impedances

$$\frac{\alpha}{\delta} Z_s, \frac{\epsilon}{\delta} Z_c \text{ and } \frac{\gamma}{\delta} Z_k$$

The proportionality factors α , β , γ and δ must be chosen so as to fulfill the following conditions.

$$\alpha = R_a q S_s$$

$$\beta = (1+q) (R_a S_s - 1)$$

$$\gamma = R_a (S_s + S_a) (1+q)$$

$$\delta = \text{any positive value}$$

$$\Sigma E = R_a (1+q) S_s$$

wherein:

10 q is the ratio between the screen grid, alternating current i_s and the anode alternating current i_a , which ratio may be considered to be constant, S_s is the mutual conductance of the characteristic curve of the anode current/screen-grid voltage, and

15 S is the mutual conductance of the characteristic curve of the anode current/control-grid voltage.

20 When these conditions are observed the amplification amounts to

$$\frac{e_2}{e_1} = S R_a$$

and this is consequently frequency-independent.

25 The impedances Z_s , Z_c and Z_k may, for instance comprise resistances R_s , R_c , R_k together with parallel condensers C_s , C_c and C_k as shown in Fig. 3. The impedances αZ_s , βZ_c and γZ_k in the anode circuit must then comprise resistances 30 αR_s , βR_c and γR_k together with parallel condensers

$$\frac{C_s}{\alpha}, \frac{C_c}{\beta} \text{ and } \frac{C_k}{\gamma}$$

35 In the same manner the impedances

$$\frac{\alpha}{\delta} Z_s, \frac{\epsilon}{\delta} Z_c \text{ and } \frac{\gamma}{\delta} Z_k$$

between the output terminals A_1 and A_2 are constituted by the parallel connections of resistances 40

$$\frac{\alpha}{\delta} R_s, \frac{\epsilon}{\delta} R_c \text{ and } \frac{\gamma}{\delta} R_k$$

and condensers

$$45 \frac{\delta}{\alpha} C_s, \frac{\delta}{\epsilon} C_c \text{ and } \frac{\delta}{\gamma} C_k$$

In Fig. 3, the coupling impedance comprises a condenser C_1 . A condenser

$$50 \frac{C_1}{\delta}$$

proportional thereto must consequently be interposed in the anode circuit. However, this blocks the direct current of the anode and must consequently be bridged by a resistance δR_1 . Since, on the one hand, this resistance may not be given a high value on account of the excessive voltage drop, which otherwise would be caused by the anode current and may, on the other hand, not be too small, since otherwise amplification of the low frequencies would depend on the frequency, a resistance R_1 is, according to a further feature of the invention, connected in parallel with the coupling condenser C_1 . In this case, the impedance δZ_1 in the anode circuit passes direct current. However, it is also proportional to the coupling impedance Z_1 so that the frequency-independency of the arrangement remains ensured.

70 When the grid circuit of a succeeding amplifying tube is connected to the output terminals A_1 , A_2 it is advisable to connect a condenser C in series with the resistance R_1 of the coupling impedance in order that the anode voltage E_a is kept remote from the grid of this succeeding tube.

This condenser C must have a sufficient capacity so that its impedance may be neglected with respect to the resistance R_1 even with the lowest frequencies to be amplified. To avoid that the considerable capacity with respect to earth of such a large condenser may affect the amplification of the high frequencies the resistance R_1 is preferably divided into two parts R between which the condenser C is connected as shown in Fig. 4.

10 The proportionality factor

$$\beta = (1+q) (R_a S_s - 1)$$

may become negative if $R_a S_s < 1$, which would involve a negative impedance βZ_c in the anode circuit, which cannot be realized in most cases. Then it is advantageous to make use of the circuit arrangements shown in Fig. 5 or 6.

The circuit arrangement shown in Fig. 5 may be deduced in the following manner from the circuit arrangement shown in Fig. 2. When interposing in the latter an impedance

$$25 \frac{1}{\delta} (1+q) Z_c$$

in series with Z_1 a proportional impedance $(1+q) Z_c$ must be interposed in the anode circuit. Together with the impedance βZ_c a positive impedance.

$$30 \Sigma Z_c = (1+q+\beta) Z_c = (1+q) R_a S_s Z_c$$

then results.

In Fig. 6, the impedance

$$35 -\frac{\beta}{\delta} Z_c$$

which is positive for negative β is connected in series with Z_1 ; in this case the impedance proportional to Z_c in the anode circuit may be entirely omitted.

40 It will be appreciated that the invention may also be used in amplifiers in which one or more of the impedances Z_k , Z_s and Z_c are equal to zero. Of course, the impedances proportional thereto, which are included in Z_a and Z_2 , are 45 then also equal to zero.

Furthermore, it is possible in an amplifying stage to compensate in another amplifying stage the influence of one or more of the impedances Z'_k , Z'_s , Z'_c and Z'_1 included in the first-mentioned amplifying stage, by interposing in the impedances Z_a and Z_2 of this other stage impedances proportional to Z'_k , Z'_s and Z'_c . In this case, the proportionality factors α , β , γ , δ must, of course be chosen in accordance with the 55 particularities of the tubes and circuit arrangements in use.

What is claimed is:

1. A wide band amplifier having uniform amplification comprising an electron discharge tube 60 having a cathode, control electrode, screen grid and anode, a voltage supply source, a common lead, a first impedance connected between said cathode and common lead, a second impedance connected between said screen grid and a third 65 impedance, said third impedance being connected to the common lead through the supply source, a coupling impedance connected between the anode and a first output terminal, a second output terminal connected to the common lead, 70 an anode circuit comprising a first resistor, a fourth impedance proportional to said second impedance, a fifth impedance proportional to said third impedance, a sixth impedance proportional to said first and a seventh impedance 75

proportional to said coupling impedance, said resistor and fourth, fifth, sixth and seventh impedances being serially connected between the anode and said third impedance, and a second resistor connected in series with a plurality of impedances proportional respectively to said first second and third impedances, said second resistor and plurality of impedances being connected across the first and second terminals.

5 10 2. An amplifier as claimed in claim 1 and wherein each of the named impedances comprises a parallelly connected resistance and capacity.

15 3. An amplifier as claimed in claim 1 and wherein the said coupling impedance comprises connected in series in the order named a first resistor element, a first condenser element, and a second resistor element, and a second condenser connected across the serially connected 20 elements.

25 4. An amplifier as claimed in claim 1 and comprising in addition a further impedance proportional to the third impedance, said further impedance being connected in series with said coupling impedance and to said anode.

5. A wide band amplifier having uniform amplification comprising an electron discharge tube

having a cathode, control electrode, screen grid and anode, a voltage supply source, a common lead, a first impedance connected between said cathode and common lead, a second impedance connected between said screen grid and a third impedance, said third impedance being connected to the common lead through the supply source, a coupling impedance connected between the anode and a first output terminal, a second output terminal connected to the common lead, an anode circuit comprising a first resistor, a fourth impedance proportional to said second impedance, a fifth impedance proportional to said third impedance, a sixth impedance proportional to said first and a seventh impedance proportional to 15 said coupling impedance, said resistor and fourth, fifth, sixth and seventh impedances being serially connected between the anode and third impedance, a second resistor connected in series with a plurality of impedances proportional 20 respectively to said first, second and third impedances, said second resistor and plurality of impedances being connected across the first and second terminals, and terminal means to impress control voltage between said control electrode and said common lead. 25
